CLAIM

The ornamental design for a three cutting wheel tubing cutter, as shown and described.

DESCRIPTION

FIG. 1 is a front view of the design, the rear view being a mirror image thereof.

FIG. 2 is a view from the left side of FIG. 1.

FIG. 3 is a view from the right side of FIG. 1.

FIG. 4 is a fragmentary front view of the upper part of the cutter shown in a fully open position with the handles broken away for convenience of illustration.

FIG. 5 is a view from the top side of FIG. 1; and,

FIG. 6 is a view from the bottom side of FIG. 1.
